WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN CONTROL.

1,299,945.

Specification of Letters Patent.

Patented Apr. 8, 1919.

Application filed March 12, 1915. Serial No. 14,029.

To all whom it may concern:

Be it known that I, WINTHROP K. HOWE, a citizen of the United States, and a resident of the city of Rochester, in the county of Monroe and State of New York, have invented new and useful Improvements in Automatic Train Controls, of which the following is a specification.

This invention relates to improvements in systems of automatic train control, and more particularly to those systems in which an electromagnet positioned on a movable vehicle governs, in some appropriate way, the movement of the vehicle and is itself controlled by the conditions along the trackway upon which the train moves.

The primary object of this invention is the production of a more simple, perfectly safe and entirely reliable arrangement of circuits and connections for energizing and keeping energized the electromagnet positioned on a movable vehicle, which magnet is employed to in some way control the movement of the vehicle.

Other objects and advantages will appear as the description of the invention progresses, and the novel features of the invention will be particularly pointed out in the appended claims.

In describing the invention in detail reference is had to the accompanying drawing comprising a single figure, which is a schematic illustration of a railway track with a train composed of two cars thereon, both of which are equipped with a train controlling device.

Numerals 1 designates one rail of a railway track, of which numeral 2 designates the other rail. One rail of the railway track is divided by means of insulating joints 3 and 4 into electrically isolated sections SA, SB and SC. At one end of each section a difference of potential is created between the two rails 1 and 2 of the trackway by means of a secondary coil, as 5¹, of a transformer, as 5, the primary coil, 5², which is connected across the line wires 6 and 7 extending the length of the trackway and connecting at some point to a suitable source of electrical energy, such, for instance, as the alternating current generator 8. At the end of each electrically isolated section remote from the end at which the difference of potential is created, there is a translating device, as 9,

connecting across the two rails of the trackway. In practice the entire trackway would probably be divided in the manner described so that a continuous series of closed circuited track circuit sections would exist.

Adjacent to each insulating joint is positioned a metallic contact ramp as 10, and just in the rear of the contact ramp 10, that is, in the direction opposite to the normal direction of traffic indicated by the arrow C, is positioned another metallic contact ramp, 65 as 11.

A difference of potential is created between ramps, as 10 and 11, and the trackway, as 2, by means of transformers, as 12 and 13, each of which includes a secondary winding, as 12¹ and 13¹, respectively, and a primary winding, as 12² and 13², respectively, each of which is connected across the line wires 6 and 7.

When no train is present upon the section SB or the section SC a difference of potential is created between ramp 10 and track rail 2 by means of the secondary 13¹ of transformer 13 on account of the following partial circuit: track rail 2, wire 23, one terminal of the secondary 13¹, secondary 13¹, the other terminal of secondary 13¹, wire 14, armature 15², wires 16, 17 and 18, armature 9¹, in its upper position, wires 19 and 20, relay 21 and wire 22 to ramp 10. If any metallic connection is made between ramp 10 and track rail 2 a flow of current will take place. A difference of potential also exists when no train is present upon the section SB between ramp 11 and track rail 2 by reason of the following partial circuit: track rail 2, wire 24, one terminal of secondary 12¹, secondary 12¹, the other terminal of secondary 12¹, wire 33, armature 9², in the upper position, and wires 26 and 27 to the ramp 11. If metallic connection is made between ramp 11 and track rail 2 a flow of current will take place.

If no train is present upon sections SB and SC and a metallic connection is made between ramp 10 and track rail 2, then a flow of current will take place which will energize relay 21, which will cause its armature 21¹ to be raised to the upper position, so that even if relay 9 is subsequently de-energized and armature 9¹ breaks contact with wire 18, a flow of current will still take place between ramp 10 and track rail 2 by

reason of the following circuit: one terminal of secondary 13¹, wire 14, armature 15², wires 16, 17 and 25, armature 21¹, wires 34 and 20, relay 21, wire 22, ramp 10, any metallic connection between ramp 10 and rail 2, track rail 2 and wire 23 to the other terminal of transformer 13¹.

A train consisting of two cars, one designated by A and the other by B, has been 10 illustrated as being upon the trackway. The automatic train control apparatus carried by each of the cars or vehicles of the train is illustrated diagrammatically and designated by the numeral 30, since the particular 15 construction of this train control apparatus forms no part of the present invention and may take any suitable form consistent with the utility and functions of the system herein shown and described. The train control apparatus 30 is so constructed as to be 20 inactive when energized and to assume automatically its active controlling condition when deenergized. This train control apparatus 30 on each car is controlled by a relay 29 having two separate windings; and 25 when either winding of this relay 29 is energized, its armature 55 is attracted so that current is supplied to the apparatus 30 from a battery 54, thereby restoring the apparatus 30 to its inactive condition, or maintaining it in that inactive condition, as the case 30 may be.

Where a number of cars, each equipped 35 with automatic train control apparatus and controlling devices in accordance with this invention, are coupled together into a train, continuous conductors or bus lines 36, 37 and 53 are provided extending between these 40 cars. The bus lines 36 and 37 are battery bus lines, being connected to a battery 35.

Normally, while the train is traveling between the ramps above mentioned at the entrances to the blocks, and while safe traffic 45 conditions ahead prevail, one winding of the relay 29 on each vehicle is normally energized by a normally closed stick circuit which may be traced as follows: commencing at the bus line 36, conductors 38 and 39, shoe contacts 40—41, conductor 42, armature 43 of the relay 29, conductor 44, lower winding of the relay 29, and conductors 45 and 46 back to the other battery bus line 37. When a car passes a ramp, its shoe 31 is 50 raised to separate the contacts 40—41, thereby interrupting the stick circuit above traced and deenergizing the lower winding of the corresponding relay 29. If this ramp is deenergized, neither of the windings of the relay 29 is supplied with current, so that 55 its armatures 43 and 55 drop. The dropping of the armature 43 opens another break in the stick circuit above mentioned, so that this circuit will not be reestablished when the shoe 31 leaves the ramp and its contacts 60 40—41 close. The dropping of the armature

55 deenergizes the train control apparatus 30 and renders it active to control the movement of the train.

If the ramp engaged by the shoe 31 of the vehicle is energized by some one of the partial circuits previously described, the relay 28 on that vehicle is supplied with current from the shoe 31 along conductor 56, through the relay 28 and conductor 57, through the car wheels or frame of the vehicle to the track rail. The energization of the relay 28, which occurs while the shoe of that vehicle is upon an energized ramp, attracts the armature 48 of the relay 28 and establishes a circuit for energizing the upper 80 winding of the corresponding relay 29, this circuit being traced as follows: commencing at the battery bus 36, conductors 38 and 47, armature 48 of the relay 28 in its upper position, conductors 49 and 50, upper winding 85 of relay 29 and conductors 51 and 46 back to the other battery bus line 37. This energization of the upper winding of the relay 29 is sufficient to attract its armatures 43 and 55, either raising them to the upper position or 90 maintaining them in that position, as the case may be, regardless of the fact that the lower winding of this relay is deenergized by the interruption of its stick circuit. Thus, when the vehicle passes an energized 95 ramp, its train control apparatus 30 is restored to its inactive condition or maintained in that condition.

When the relay 28 on any one of the cars of a train is energized, it not only energizes the upper winding of the corresponding relay 29, but also the upper winding of the relay 29 on each of the other cars, since the raising of the armature 48 of any relay 28 connects the bus line 36 to the bus line 53, and the upper 100 windings of the several relays 29 are connected in multiple across the bus lines 37 and 53. For example, when the relay 28 on the first car shown on the drawing is energized from the trackway circuits, the raising 105 of its armature 48 connects the bus line 36 to the bus line 53 by conductors 38 and 47, armature 48 and conductors 49 and 52, so that current is supplied to the relay 29¹ on each rear car by a circuit which in the 110 case of the rear car illustrated may be traced as follows: commencing at the battery bus line 36, conductors 38 and 47, armature 48, conductors 49 and 52, bus line 53 to rear car conductors 52¹ and 50¹, relay 29¹, and conductors 51¹ and 46¹ to the other battery bus line 37.

In this way, the train control apparatus 30 on each of the cars of a train will be automatically restored to the inactive condition, whenever the shoe on any one of 115 these cars is in contact with an energized ramp.

The operation of the whole system may be described as follows: If the train consisting of the cars A and B approached the in- 120

sulating joint 3 when moving in the direction of the arrow C, that is, in the normal direction of traffic, when no train was present upon the section SB in the direction of traffic, then relay 9 would have been energized, and, consequently, a difference of potential would have existed between ramp 11 and track rail 2, which, as previously explained, would have energized relay 28 and 10 would have thus caused the armatures of relay 29 on each car to be raised to the upper position, as shown, if they were not already in that position, so that the train controlling apparatus 30 on each car would have been 15 energized. As the train progresses and the first contact shoe 31 carried thereby engages with the ramp 10, if the sections SB and SC are not occupied, the relay 28 is again energized to maintain the relay 29 energized 20 and keep the train control apparatus 30 energized. This action would have taken place due to the fact that a metallic connection was made between ramp 10 and track rail 2, which, as hereinbefore explained, would have caused relay 21 to become energized and its armatures 21¹ to be raised to the upper position, so that just so long as the metallic shoe 31 of the car A rested upon the ramp 10 the relay 21 would 30 remain energized, and a flow of current continue through relay 28, so that even after the first wheels of the car A passed the insulating joint 3 and deenergized the relay 9, a flow of current would still continue through 35 the relay 28.

The relay 21 as used in this invention is for the purpose of preventing a car equipped as shown from causing its own train controlling mechanism as 30 from becoming deenergized by the entrance of the train 40 itself into an unoccupied track circuit section, and it performs this function by closing a shunt path about the track relay contact of the section which the train enters, in 45 case, and only in case, a difference of potential existed between the ramp with which it is then in contact and a track rail, when the apparatus of the car first contacted the contact ramp.

50 The utilization of relay 21 for the purpose as described, also requires that the contact ramp 10 shall be of such length that the first shoe, as 31, of an approaching train to contact with it must not break contact with it until the shoe of the next car of the train has contacted with contact rail 10, and, furthermore, that no shoe of the train, except the shoe of the last car, must break contact with the contact ramp 10 until the shoe 55 of the following car has contacted with contact ramp 10. This must be so because in order to maintain the energization of relay 21 after once being energized, there must continue to exist a metallic connection between the ramp 10 and rail 2, which in the

construction shown can only be made to exist by the contact of a contact shoe as 31 with a contact ramp as 10. That is, relay 21 may be considered a stick relay which is picked up by the contact of the first shoe, as 31, of a train with the contact ramp 10, and is then maintained in its picked up condition by the continuing contact of that same shoe or a similar shoe.

The relay 21 must be first energized by 75 the first shoe of the first car of the train to contact with ramp 10, and it must be maintained energized until the last shoe of the last car of the train has passed off from the contact ramp 10, because otherwise the armature 21¹ would fall and break contact with wire 25, and if this occurred before all of the shoes of a train had passed the contact ramp 10 the brake controlling mechanism 30 on all of the cars of the train, of which the 80 shoes contacted with ramp 10 after relay 21 became deenergized, would be deenergized and so act to control the movement of the train, because such shoes would not contact with ramp 10 when a difference of potential 85 existed between ramp 10 and track rail 2, because such difference of potential would be destroyed by the dropping of armature 9¹ of relay 9, caused by the entrance of the head 90 end of the train upon the section controlling 95 relay 9.

If a train such as one composed of the cars A and B should pass the contact ramp 10 when a train were present upon the section SC controlling relay 15, then the brake 100 controlling mechanism 30 of the cars of the train would be deenergized and would act to control the movement of the train, but if at the time the train reached contact ramp 33 the preceding train which had been on the section SC controlling relay 15 had moved off from that section, then it would be proper 105 to momentarily reenergize the brake controlling mechanism 30 on the train, thus restoring it to normal condition so that if the preceding train were in the section ahead of the section SC controlling relay 15 when the train composed of cars A and B contacted ramp 32 by means of a shoe, as 31, then the 110 brake controlling mechanism 30 would again be deenergized, and starting from normal condition would again act to control the movement of the train in exactly the same way that it did when the train passed the ramp 10. While the brake controlling 115 mechanism 30 may take various forms suitable for use in connection with the trackway controlling circuits embodying this invention, these trackway controlling circuits have special utility and advantages when used in connection with brake controlling mechanism of the cyclic type, such as shown and described in the patent to P. J. Simmen, 1,150,309, August 17, 1915. On account of 120 the controlling functions performed by the 125 130

two ramps at the entrance to each block, as the ramps 11 and 10, these respective ramps may be conveniently termed restoring ramps and initiating ramps.

5. Although applicant has shown ramps 11 and 33 as distinct and separate from ramps 10 and 32, it is to be understood that such is a preferred and not an absolutely necessary construction. By separating the ramps 10 any undesired effects resulting from the flow of propulsion current to the ramps is avoided where electric propulsion is used for the trains.

Although I have particularly described 15 the construction of one physical embodiment of my invention, and explained the operation and principle thereof; nevertheless, I desire to have it understood that the form selected is merely illustrative, and does not 20 exhaust the possible physical embodiments of the idea of means underlying my invention.

What I claim as new and desire to secure by Letters Patent of the United States, is 25 1. In an automatic train control system, in combination: a trackway divided into electrically isolated sections; a source of current connected to the rails of each section and a translating device connected to the 30 rails of each section forming track circuit sections; ramps, one associated with each track circuit section; a partial circuit for each ramp including said ramp, a source of current, a circuit controller governed by the 35 translating device of the track circuit section immediately ahead of the ramp, a relay, and a track rail; a train; means on the train to complete said partial circuit and so energize said relay; a circuit for shunting said 40 circuit controller including another circuit controller controlled by said relay which is closed by the energization of said relay; and means on the moving vehicle for controlling the movement thereof controlled by the last 45 named means.

2. In an automatic train control system, in combination; a trackway divided into track circuit sections each including a translating device and a source of current; ramps, 50 one positioned at the entrance to each track circuit section; a partial circuit for each ramp including said ramp, a source of current, a circuit controller governed by the translating device of the track circuit section 55 immediately ahead of the ramp, a circuit controller controlled by the translating device of the section ahead of the last named section, a relay, and a track rail; a train; means on the train to complete the partial 60 circuit and so energize said relay; a circuit for shunting said first named circuit controller including another circuit controller governed by said relay which is closed by the energization of said relay; and means 65 on the moving vehicle for controlling the

movement thereof controlled by the last named means.

3. In a system for protecting railway traffic, in combination: a track divided into track circuit sections each having a track 70 relay; a contact rail associated with each track circuit section; a conductor leading to each contact rail; a circuit controller included in said conductor and opened when the corresponding track relay is deenergized; a normally open shunt for the contacts of said circuit controller; and means for closing said shunt, said means being initially dependent on said circuit controller being closed and after its initial operation being 80 effective to maintain said shunt closed so long as current flows in said conductor. 75

4. In a system for protecting railway traffic, in combination: a track divided into track circuit sections each having a track 85 relay; a contact rail associated with each track circuit section; a conductor leading to each contact rail; a circuit controller included in said conductor and opened when the corresponding track relay is deenergized; a 90 normally open shunt for the contacts of said circuit controller; a translating device included in said conductor; and a second circuit controller for closing said shunt which is governed by said translating device and 95 which is closed when said translating device is energized.

5. In a system for protecting railway traffic, in combination: a track divided into track circuit sections each having a track 100 relay; a contact rail associated with each track circuit section; a conductor leading to each contact rail; means controlled by the track relay of the corresponding section for opening a break in said conductor when that 105 track relay is deenergized; means for closing said break in said conductor; and electro-responsive means included in said conductor between said first mentioned means and the contact rail for operating said last mentioned 110 means when and so long as there is current flowing through said contact rail to a track rail.

6. In a system for protecting railway traffic, in combination: a track divided into 115 track circuit sections each having a track relay; a contact rail associated with each track circuit section; a conductor leading to each contact rail; means controlled by the track relay of the corresponding track section for opening a break in said conductor when that track relay is deenergized; a normally open shunt for said break; a circuit controller for closing said shunt; a stick relay for operating said circuit controller 120 and included in said conductor between said break and the contact rail. 125

7. In a system for protecting railway traffic, in combination: a track divided into track circuit sections; a traffic controlling 130

- device associated with each track circuit section; a controlling circuit for each device governed by the corresponding track circuit section and interrupted when that track circuit section is occupied; normally inoperative means governed by each track circuit section and rendered operative by the presence of a train adjacent to the corresponding device, subject to the control of the corresponding track circuit section, for establishing said controlling circuit independently of the control of said circuit by the corresponding track circuit section.
8. In a system for protecting railway traffic, in combination: a track divided into track circuit sections; a contact rail located adjacent to the entrance to each track circuit section; a partial circuit associated with each contact rail for creating a difference of potential between that contact rail and a track rail; means controlled by the corresponding track circuit section for governing said partial circuit; a second contact rail associated with each track circuit section and located in advance of the first mentioned contact rail with respect to the normal direction of traffic; a partial circuit associated with each second contact rail for creating a difference of potential between that second contact rail and a track rail; and means controlled by the corresponding track circuit section and the track circuit section next in advance thereof for governing said last mentioned partial circuit.
- 35 9. In an automatic train control system, the combination with a track divided into blocks, of two separate impulse transmitting devices located adjacent to the entrance end of each block and each having an inactive 40 and an active controlling condition, means associated with one of said impulse devices of each block for causing that device to have its active controlling condition when the corresponding block is not occupied, and means 45 associated with the other of said impulse devices of each block for causing that device to have its active controlling condition when the corresponding block and also the next block in advance thereof are not occupied, the first 50 mentioned impulse device of each block being located in the rear of the other with respect to the normal direction of traffic so as to be encountered first by a passing train.
10. In an automatic train control system, the combination with a track divided into track circuit blocks each having a track relay, of two separate impulse transmitting devices located adjacent to the entrance end of each block, a controlling circuit for one of 55 the impulse devices of each block including a front contact of the track relay of the corresponding block, and a controlling circuit for the other of said impulse devices of each block including a front contact of the track 60 relay of the corresponding block and also a front contact of the track relay of the block next in advance thereof, the first mentioned impulse device of each block being located in the rear of the other with respect to the normal direction of traffic so as to be encountered first by a passing train.
- 65 11. In an automatic train control system, the combination with a track divided into blocks, of separate restoring and initiating impulse transmitting devices located adjacent to the entrance end of each block, the initiating impulse device being in advance of the restoring impulse device with respect to the normal direction of traffic, means dependent on traffic conditions in the corresponding block for controlling the restoring impulse device at the entrance thereof, and means dependent on traffic conditions in both the corresponding block and the next block in advance thereof for controlling the initiating impulse device.
- 70 12. In an automatic train control system, the combination with a track divided into blocks, of separate restoring and initiating impulse transmitting devices located adjacent to the entrance end of each block and each having an energized and a deenergized 75 controlling condition, the initiating impulse device being in advance of the restoring impulse device, an energizing circuit for each restoring impulse device responsive to traffic conditions in the corresponding block and also in the next block in advance thereof, and means dependent on the last mentioned circuit for maintaining the corresponding initiating impulse device in the same controlling condition during the passage of a train thereby.
- 80 13. In an automatic train control system, the combination with a track divided into track circuit blocks, of a train including a number of vehicles each similarly equipped, means for transmitting impulses from the track to the train including an element carried by each vehicle and track elements located one adjacent to the entrance end of each block, a controlling circuit for each track element, means for causing a break in 85 said controlling circuit when the corresponding block is occupied, and means initially dependent on the continuity of said controlling circuit for maintaining it closed independent of said means so long as an element on any one of the vehicles cooperates with the corresponding track element.
- 90 14. In an automatic train control system, the combination with a track divided into blocks, of a train including a number of vehicles each carrying a contact shoe, a ramp located adjacent to the entrance end of each block and longer than the distance between any two successive contact shoes of the train, 95 a partial circuit associated with each ramp,
- 105 110 115 120 125 130

circuit controlling means governed by the track circuit of the corresponding block for causing a break in said partial circuit when said block is occupied by any part of a train, 5 and means initially dependent on the flow of current in said partial circuit for maintaining the continuity thereof independent of said circuit controlling means so long as current is caused to flow in said partial circuit by the coöperation of a contact shoe with the corresponding ramp.

15. In an automatic train control system, the combination with a track divided into blocks, of two separate impulse devices at 15 the entrance to each block, means for causing the impulse device first encountered by a passing train moving in the normal direction of traffic to indicate safety when the corresponding block is not occupied, means 20 for causing the other impulse devices last encountered by a passing train moving in the normal direction of traffic to indicate safety when both the corresponding block and the next block in advance are not occupied, automatic train control apparatus on a 25 passing train for regulating the movement thereof and having a tendency to assume its operating condition, said apparatus being adapted when set into operation to continue 30 in operation until restored, and control means on the train normally preventing the operation of said apparatus but acting under the influence of said impulse devices to continue such prevention or allow said apparatus 35 to operate depending on whether said impulse devices indicate safety or danger respectively, said control means also acting when the train passes an impulse device indicating safety to restore said apparatus if 40 it has been previously set into operation.

16. In an automatic train control system, the combination with a track divided into blocks, of a train including a number of vehicles similarly equipped, impulse transmitting 45 means comprising an element on each vehicle adapted to coöperate with elements along the track one at the entrance to each block, a control circuit for causing each trackway element to indicate safety 50 when both the corresponding block and the next block in advance are not occupied, and means governed by the coöperation of the vehicle carried element with a trackway element and initially dependent upon the controlling 55 circuit of said trackway element for causing it to continue its safety indication during the passage of the train thereby and irrespective of the entrance of such train into the corresponding block, whereby when 60 the train passes a trackway element indicating clear, each of the vehicles of the train will receive a clear impulse regardless of the entrance of the front end of such train itself into the corresponding block.

65 17. In an automatic train control system,

the combination with a track divided into blocks, of a train including a number of vehicles similarly equipped, impulse transmitting means comprising an element on each vehicle adapted to coöperate with elements along the trackway at the entrance to each block, trackway circuits for causing each trackway element to indicate safety when the corresponding block and the next block in advance are not occupied, and means 70 governed by said track circuits and responding to the coöperation of a vehicle carried element with a trackway element for causing said trackway element to maintain its existing controlling condition during the passage of a train and irrespective of the presence of part of such train in the corresponding block.

18. In an automatic train control system, the combination with a track divided into 85 blocks, of a train including a number of vehicles each equipped with train control apparatus for regulating the movement thereof and having a tendency to assume an operating condition, said apparatus being 90 adapted when set into operation to continue in operation until restored, a restoring impulse device on the track at the entrance to each block, an initiating impulse device at the entrance to each block and located in advance of the restoring impulse device with respect to the normal direction of traffic, trackway circuits for causing energization of the restoring impulse device when the corresponding block is not occupied and of the 95 initiating impulse device when both the corresponding block and the next block in advance are not occupied, means governed by 100 said trackway circuits for maintaining the initiating impulse device of each block in 105 its existing condition during the passage of the train irrespective of the entrance of such train into the corresponding block, and control means on each vehicle normally preventing operation of its train control apparatus 110 but acting under the influence of said impulse devices to continue such prevention or allow said apparatus to operate depending on whether the impulse device is energized or deenergized respectively, said control 115 means also acting when the vehicle passes an energized impulse device to restore said apparatus if it has been previously set into operation.

19. In an automatic train control system, 120 the combination with a track divided into blocks each having a normally closed track circuit, of an impulse device at the entrance to each block adapted to transmit controlling impulses to passing trains, means for 125 causing each impulse device to assume different controlling conditions in accordance with traffic conditions in the corresponding block and the next block in advance, and means including a stick relay for causing 130

each impulse device to be maintained in the same existing controlling condition during the passage of a train thereby and irrespective of the entrance of such train into the 5 corresponding block.

20. In an automatic train control system, the combination with a track divided into blocks each having a normally closed track circuit, of an impulse device at the entrance 10 to each block adapted to transmit controlling impulses to passing trains, a control circuit for each impulse device governed by the track circuit of the block next in advance of the corresponding block, a normally open 15 break in said controlling circuit, means including a stick relay for closing said break during the passage of a train past the corresponding impulse device, and an energizing circuit for said stick relay governed by the 20 track circuit of the corresponding block.

21. In an automatic train control system, the combination with a track divided into blocks each having a normally closed track circuit, a train including a number of vehicles each equipped with automatic train 25 control apparatus which are interconnected for simultaneous operation, an impulse device at the entrance to each block adapted to transmit controlling impulses to the passing vehicles of a train, and means responsive 30 to traffic conditions in the corresponding block and the next block in advance for governing each impulse device, and means for causing each impulse device to be maintained in the same existing controlling condition during the passage of a train thereby. 35
